UNITED STATES PATENT OFFICE.

WILLIAM G. ASHBY, OF FRANKLIN, VIRGINIA.

DESIGN FOR A CAMPAIGN-BUTTON.

SPECIFICATION forming part of Design No. 26,755, dated March 16, 1897.

Application filed July 30, 1896. Serial No. 601,099. Term of patent 3½ years.

To all whom it may concern:

Be it known that I, WILLIAM G. ASHBY, a citizen of the United States, residing at Franklin, in the county of Southampton and State 5 of Virginia, have invented and produced a new and original Design for Campaign-Buttons, of which the following is a specification, reference being had to the accompanying drawings, in which—

10 Figure 1 is a front elevation or face view, and Figs. 2 and 3 are side views.

The leading feature of my design consists in a central portion ornamented with the head or portrait of the candidate, from which central portion radiate convexly curved paddle-shaped projections, the whole resembling in its general contour or appearance a sunflower.

Referring to the drawings, A designates the body of the article, which is circular in its general contour and comprises a circular central portion a, ornamented with the head or portrait of the candidate, as shown at b, and a circumferential series of radiating paddle-

shaped projections a', convexly curved, as shown in the sectional views, and surrounding said ornamental central portion. 25

In practice the radiating projections a' may be colored in gilt and the central portion a in bronze.

Projecting from the body A at the back is 30 a pin-shaped member or shank c.

What I claim is—

The design for a campaign-button, consisting of the central portion a ornamented with the head or portrait of the candidate, and the 35 series of radiating paddle-shaped projections a' surrounding said central portion and convexly curved, substantially as shown and described.

In testimony whereof I affix my signature 40 in presence of two witnesses.

WILLIAM G. ASHBY.
